UNITED STATES PATENT OFFICE.

CHARLES STERN AND GEORGE F. EGAN, OF JERSEY CITY, NEW JERSEY.

SIGNALING MECHANISM FOR VEHICLES.

Application filed April 21, 1920. Serial No. 375,604.

To all whom it may concern:

Be it known that CHARLES STERN and GEORGE F. EGAN, citizens of the United States, residing at Jersey City, in the county 5 of Hudson and State of New Jersey, have invented new and useful Improvements in Signaling Mechanism for Vehicles, of which the following is a specification.

The present invention relates to improvements in signaling mechanism for vehicles, and it more particularly refers to that class 10 of signals which are used to denote proposed movements, changes in direction, or stoppages of the vehicle carrying the signal. It is an object of the present invention to provide a signal of this character which 15 may accurately apprise drivers of other automobiles or vehicles of intended changes in the movements or stoppages by the vehicle carrying the signal before the latter actually engages in such movements or stoppages, to the end that traffic may be the better controlled and accidents prevented.

Another object of the present invention 25 resides in providing a signal mechanism having numerous displays arranged and organized in a compact relation, so that they may be quickly exhibited and clearly seen both in daylight and at night.

A further object of the invention lies in providing an improved signaling mechanism adapted to be mounted in conjunction with a signal lamp and having compact and simple-operating mechanism for selectively 35 displaying the several directions from a point at or near the driver's seat in the vehicle.

With the foregoing and other objects in view, as will become apparent to those 40 skilled in this art, the invention will be more fully described hereinafter in connection with the accompanying drawings, wherein like reference symbols denote like or corresponding parts throughout the several 45 views, and in which

Fig. 1 is a top plan view of an automobile on which is shown the improved signaling mechanism constructed in accordance with the present invention.

Fig. 2 is a front elevation of the auto-

mobile showing the application of the signaling mechanism to the front thereof.

Fig. 3 is a view in rear elevation of the automobile illustrating the improved signaling mechanism as it appears to those in back 55 of the vehicle.

Fig. 4 is a top plan view on an enlarged scale of the improved signaling mechanism.

Fig. 5 is a horizontal sectional view taken therethrough.

Fig. 6 is a transverse sectional view through the signaling mechanism.

Fig. 7 is a vertical longitudinal sectional view through the same.

Fig. 8 is a view in elevation of the lamp, 65 tube, and journal stud.

Fig. 9 is a perspective view of the housing employed.

Fig. 10 is also a perspective view of the signal display drum or casing.

Fig. 11 is a longitudinal sectional view through the rack and pinion actuating mechanism and appurtenant parts.

Fig. 12 is a view partially in elevation and partially in section of the controlling device at the driver's seat.

Fig. 13 is a vertical sectional view through the quadrant of the controlling device, and

Fig. 14 is an edge elevation of the quadrant.

Referring more particularly to the drawings, the improved signaling device is preferably constructed in accordance with the mechanical embodiment illustrated in detail in Figs. 4 to 10 inclusive, to which reference will be now more specifically made.

The signaling mechanism is encased in a housing 1 appearing in perspective in Fig. 9 and composed of a cylinder of metal or some other appropriate material closed at 90 its ends by flanged heads 2 and 3. The flanges fit over the exterior edges of the cylinder 1, and have tight frictional engagement therewith serving to avoid rattling of these parts when the vehicle is in motion, 95 and at the same time allowing the heads to be readily removed for the purpose of gaining access to the interior of the cylinder 1.

In the cylinder 1 are made elongated openings 4 and 5, preferably enclosed by glass, 100

- mica, or other translucent material which may have its longitudinal edges fitted in U-shaped strips 6 and 7 carried by the housing at opposite sides of the openings therein.
- 5 The heads 2 and 3 are shown as respectively provided with openings 8 and 9 of unequal diameters to permit of receiving parts as more particularly referred to hereinafter.
- 10 At the side thereof next the vehicle, the cylindrical portion 1 of the housing is offset out of the true cylindrical contour providing a reinforcing rib 10 of a substantially rectangular form in cross section lying longitudinally of the housing and which furnishes a convenient abutment for the securing of a supporting bar 11.
- Bolts or other fastening means 12 may be employed to effect the connection between 15 the bar 11 and reinforcing rib 10. The bar 11 is provided with a head 13 slotted as at 14 to receive the upturned end or hook 15 of a bracket 16 carried by a suitable part 20 of the vehicle to which the signaling mechanism is attached.
- A set screw 17 is threaded in the head 13 in position to bind against the hook 15 to 25 secure the signaling mechanism on the bracket.
- 30 Of course this is merely illustrative of one means of securing the signaling mechanism on the vehicle, and it will be quite obvious that other means of accomplishing this same end may be resorted to if desired 35 or found more convenient.
- The bar 11 extends at one end beyond the housing 1 where it acts to support a signal lamp 18 by means of a set screw 19 passing through the extension of the bar 11 and 40 threaded into a portion of the lamp casing. The lamp here illustrated is of the type of signal lamp at present in general use on the rear of automobiles and displays a red bull's eye 20 to the rear of the machine.
- 45 The construction of this lamp is modified to the extent that an opening 21 is made through one side thereof, and in the opening is fixed a ring or collar 22 forming part of a tube 23 of slightly lesser diameter having 50 one end thereof fitted into the interior of the collar or ring 22 and secured therein in any suitable manner.
- The collar or ring 22 has an inwardly turned flange 24 at the side thereof next the 55 lamp forming an abutment for the peripheral edge of a partition 25 of glass, mica, or other suitable translucent material, the other edge of which is confined in place by the adjacent end of the tube 23.
- 60 In the lamp casing 18 is shown both oil and electric sources of illumination respectively represented at 26 and 27, although either may be dispensed with and the other used alone. A reflector or mirror 28 is placed in the interior of the lamp casing 65 18 at the side thereof opposite the opening 21, and such a reflector acts to direct the rays from the illuminating source axially through the partition 25 and into the tube 23. The interior of this tube 23 is preferably highly polished to act as a reflecting surface for directing the rays of light received from the illuminating source in the lamp through slots 29 and 30 made therein in substantial radial alinement with the 70 openings 4 and 5 respectively in the housing 1.
- A flanged cap 31 is provided to close the outer end of the tube 23, the flange thereof fitting over the end portion of said tube 80 and being secured thereon in any suitable manner.
- The inner face of the cap 31 is also preferably polished to a high degree to act as a reflecting surface aiding in the diffusion 85 of the light through the slots 29 and 30. The cap 31 carries a journal-stud 32 extending coaxially with the tube 23 and having both ends 33 and 34 threaded.
- A nut portion 35 is provided between the 90 threaded ends of the journal stud to receive a wrench or other tool whereby the stud may be turned, for instance, in screwing it into the cap 31 which is provided with a central and threaded opening to receive the 95 same. Adjacent the inner end of the nut portion 35 the stud 32 is further supplied with a circular flange 36 adapted to take against the outer face of the cap 31 when the stud is screwed home therein.
- Fitted about and enveloping the tube 23 100 is a signal drum or casing, shown more particularly in Fig. 10, and composed of flanged heads 37 and 38, between which extend strips 39 spaced-apart and receiving 105 glass, mica, or other translucent panels 40 whereon is displayed the various signal indicia. The ends of the strips 39 are received between the flanges of the heads 37 and 38 and between cooperating flanges on 110 discs 41 and 42 fitted against the inner sides of said heads and secured thereto in any desirable manner.
- Between the heads also extend rods or 115 bolts 43 having heads or nuts 44 exterior of the heads 37 and 38 for holding the same in place. The panels 40 are supplied with suitable signal indications as, for instance, the words "Back," "Slow," "Stop," "Left," and "Right." Also an additional panel may 120 contain the word "Doctor," as shown in Fig. 10 to indicate that the proprietor of the machine carrying the signal is entitled to right of way in emergency cases. Of course, this particular panel may contain advertising matter or any other display that may be found suitable or desirable to have it 125 contain.

The signal drum or casing is provided with a relatively large opening at the end thereof next the lamp, this opening being of a suitable size to admit of journaling the 5 head 37 on the band or collar 22 of the tube. This end of the signal casing or drum is freely rotatable on the band or ring 22.

The other end of the signal drum is provided with a threaded perforation of small 10 diameter adapted to removably receive the threaded end of a bearing 45, the central part of which is shown in Fig. 7 to take against the outer side of the head 38.

The bearing 45 also fits snugly within the 15 opening 9 in the head 3 of the housing 1.

A pinion 46 is formed on, or affixed to, the bearing 45 beyond the head 3 of the housing where it receives a rack 47 fitted to reciprocate horizontally in a casing 48. The casing 20 48 also is made with a lower bulged portion 49 to receive the pinion 46.

The rack 47 is provided with a rod 50 extending from one end thereof and operating in a closed tube 51 threaded at its opposite 25 ends into coupling pieces 52 and 53, the latter of which is secured to the casing 48. In the coupling piece 52 is received one end of a hollow flexible shaft 54 removably held therein as by a set screw 55.

30 A flexible rod 56 is slidably mounted in the shaft 54 and is connected to the rod 50, as by a coupling head 57 shown in Fig. 11. Of course, other types of connections may be made.

35 The flexible rod or connection 56, together with the flexible hollow shaft 54 which encases the former, extends beneath the vehicle or through the same to a convenient point of operation within the body thereof preferably 40 at or about the driver's seat.

The steering column 58 indicated in dotted lines in Fig. 12 is found to be a convenient part to which to attach a controlling mechanism for the signals, which controlling mechanism is preferably located just beneath the steering wheel.

45 A clamp 59 or other form of device engages about the steering column 58, and has a socket 60 in which to receive a stud 61 projecting from the controlling mechanism.

50 As shown in Figs. 12, 13, and 14 the controlling mechanism preferably embodies a frame 62 in which is secured a quadrant 63, hollow in its interior to provide a space in which a controlling lever 64 may freely swing. A pivot 65, preferably in the form 55 of a screw which may be removed from one side of the quadrant, is employed to act as a fulcrum for the lever 64.

60 The lever is provided with a handle 66 projecting beyond the arcuate edges of the quadrant plates and forming a convenient means in a convenient position for swinging the lever.

A latch 67 is pivoted on the lever as at 65 68 and carries a tooth 69 bridging the slot between the quadrant plates so as to simultaneously enter registering pairs of notches 70, provided in the arcuate edges of these plates.

A coil spring 71 is interposed between the handle 66 and the latch 67 for normally urging the tooth 69 into the pair of notches presented to it at any given time. The squeezing of the latch 67 by the hand of the 75 operator, while in the act of grasping the handle 66, will operate to rotate the latch about its pivot point 68, and withdraw the dog or tooth 69 from the pair of notches it may engage, and thus the lever will be free 80 to be swung over the arcuate edges of the quadrant plates.

A panel or plate 72 is carried by one of the quadrant plates at the arcuate edge thereof, and, as shown in Fig. 14, is supplied 85 with designations corresponding to those carried by the panels 40 of the signal drum. The various designations on the panel or plate 72 are arranged opposite the pairs of notches 70 so that the operator may know 90 that by bringing the tooth or dog 69 of the latch into engagement with any of the pair of notches opposite the particular signal desired that the signal designated by the word to the left of the pair of notches will be that 95 displayed by the signal drum through the opening 4 in the housing 1.

The quadrant 63 is provided with tubular extensions 73 and 74 at both lower and upper ends thereof, in which to receive the 100 flexible shafts 54. Set screws 75 secure the shafts removably in the tubular extensions. The tubular extensions communicate with the space between the quadrant plates and admit the flexible rods 56 thereto. The 105 flexible rods 56 are secured to the lever 64 in any suitable way as indicated at 76.

As shown in Figs. 1, 2, and 3 an automobile or other motor vehicle, designated generally at 77 is provided with the improved 110 signaling mechanism on both the front and rear portions thereof. The signaling mechanism at the rear is held on a bracket such as 16, secured to the back of the body portion of such vehicle, while the front signal 115 is carried by a suitable bracket affixed to the neck of the radiator 78.

The two signal mechanisms are constructed as described in connection with Figs. 4 to 10 inclusive, and the parts thereof which 120 appear are similarly numbered.

Flexible shafts such as 54 extend from both the front and rear signals to the controlling mechanism on the steering post 58, and these two flexible shafts enter the quadrant plates from above and below as described in conjunction with Figs. 12, 13, and 14.

The idea is to so dispose the signal drums that the panels thereon will display the same signal both at the front and rear of the vehicle. For instance, the front signaling mechanism shown in Fig. 2 indicates that the vehicle is about to be turned at a street intersection to the right, and in Fig. 3 the rear signal displays this identical indication to drivers of oncoming vehicles in the rear.

In like manner, the several other signal indications will be simultaneously and identically displayed by both mechanisms. The front signaling mechanism is particularly desirable as it informs traffic officers as to proposed changes in directions of a vehicle and assists in the expeditious directing of traffic.

The rear mechanism is useful in informing drivers of following vehicles as to intended movements of a preceding vehicle, and dispenses with the dangerous practice of throwing out the arm from the side of the vehicle.

Should a driver of a vehicle carrying the improved signaling mechanism as heretofore described desire to turn at a street intersection toward the right, he will, if he carries out the idea involved in the present invention, previously signify his intention to do so by moving the controlling lever 64 to a position shown in Figs. 12, 13, and 14 with the latch tooth 69 engaging the notches opposite the word "Right".

This lever 64 acting on the flexible rods 56 will communicate the necessary motion to the racks 47 at both the front and back signaling mechanisms to cause the pinions 46 to rotate the signal drums to positions where they will display the word "Right" in registry with the openings 4 in the housings 1. If at night, the lamp will illuminate this signal panel.

In case an oil lamp is used, the glass or mica partition 25 will exclude soot from the interior of the tube and signal drum, and it will also prevent flame igniting the panels 40 which are generally of celluloid or some such highly inflammable material.

The light from the lamp will not only illuminate the signal indication on the signal drum, but it will also shine through the slot 30 in the tube 23 and through the opening 5 in the housing 1, casting its rays on the automobile license plate, indicated at 80 and carried on supports 81 held on the housing or suitable part of the vehicle.

We have described preferred and satisfactory constructions, but it will be obvious that various changes and modifications may be made in the herein described embodiment of the invention provided such changes and modifications fall within the scope of the appended claims.

What is claimed is:

1. A vehicle signal comprising a lamp, a non-rotatable tube arranged to receive light through one end from the lamp, said tube having two slots therein angularly displaced, a rotary signal drum fitting about said tube and having translucent panels, means to rotate the drum, and a fixed housing having two angularly-displaced slots to agree with the slots in the tube and enveloping the drum and tube.

2. A vehicle signal including a housing having a plurality of slots therein, means whereby said housing may be secured on a vehicle, a signal drum rotatable in the housing and composed of translucent panels bearing signal indicia, means in connection with said drum and operable from the driver's seat of the vehicle to rotate the drum to selectively bring the panels thereof in registry with one of the slots in said housing, a lamp at one end of said housing and drum, and a tube extending through the housing and drum and in communication with the lamp at one end to receive light therefrom, said tube having slots therein to permit the rays from the lamp to issue through the slots in said housing and the translucent panel in registry therewith.

3. A vehicle signal including a signal lamp having an opening in one end thereof, a tube extending in alinement with the opening, a translucent partition between said lamp and the interior of the tube, said tube being slotted, a signal drum rotatable about the tube and being co-axial with the tube 100 and lamp opening and composed of panels bearing signal indicia, a housing for the drum having a slot therein, and means for turning said drum to selectively bring the several panels in registry with the opening 105 in the housing and the slot in the tube.

4. A vehicle signal including a lamp having an opening in one side thereof, a tube extending in alinement with the opening and having a slot therein, a signal drum rotatable about the tube and composed of removable heads, frame strips connected between said heads, translucent panels secured in said frame strips and having signal indicia thereon, means for securing said heads 110 on said frames, a housing for the drum having a slot therein, and means to rotate the drum.

5. In combination with a vehicle, rotatable signal means placed at the front and rear of said vehicle and having several display positions for indicating different proposed movements of the vehicle, a controlling quadrant secured in the vehicle, a lever moving over said quadrant, means to secure 125 said lever in various positions of adjustment corresponding to the display positions of the signal means, an indicating panel

carried by the segment and extending angularly to the path of the lever for showing to the operator the various display positions of the signal means relatively to said lever, 5 flexible shafts extending from said signal means to said quadrant at opposite sides of the lever, means to receive and securing the ends of said flexible shafts in said quadrant, and flexible connections engaging with the 10 signal means and passing through said flexible shafts, said connections being coupled at opposite sides to said lever for simultaneous movement.

6. A signal comprising a source of illumination, a tube having one end in connec- 15

tion with said source and having slots in the front and rear portions thereof, a drum enveloping the tube and comprising a number of separated strips, heads connecting the strips, panels slidably received in the strips, 20 means for securing the strips in the heads, a collar carried by the illumination source and rotatably receiving one of the drum heads and also forming a support for the adjacent end of the tube, a housing having 25 slots enveloping the drum, means to support the housing on the vehicle, and means to rotate the drum.

CHARLES STERN.
GEORGE F. EGAN.
